US00D830402S

(12) **United States Design Patent** (10) Patent No.: US D830,402 S
Javed et al. (45) Date of Patent: ** Oct. 9, 2018

- (54) **PORTION OF A DISPLAY PANEL WITH A GRAPHICAL USER INTERFACE COMPONENT FOR FLIGHT OPERATIONS MANAGEMENT**

(71) Applicant: **GE Aviation Systems LLC**, Grand Rapids, MI (US)

(72) Inventors: **Waqas Javed**, Dubai (AE); **Philip Balagtas**, San Francisco, CA (US); **Masaki Akiyama**, Oakland, CA (US)

(73) Assignee: **GE Aviation Systems LLC**, Grand Rapids, MI (US)

(**) Term: **15 Years**

(21) Appl. No.: 29/610,526

(22) Filed: Jul. 13, 2017

CLAIM

The ornamental design for a portion of a display panel with a graphical user interface component for flight operations management, as shown and described.

DESCRIPTION

The FIGURE is a front view of a portion of a display panel with a graphical user interface component for flight operations management according to our new design. The broken line showing of a display panel with graphical user interface is included for the purpose of showing portions of the article which form no part of the claim.
